REFRIGERATOR CABINET

Donald E. Dailey, Center Township, Vanderburgh County, Ind., assignor to Servel, Inc., New York, N. Y., a corporation of Delaware

Application December 15, 1954, Serial No. 33,574

Term of patent 14 years

(Cl. D67—3)

Fig. 1 is a perspective view showing the front and one side of a refrigerator cabinet embodying my new design;

Fig. 2 is a front elevational view of the refrigerator cabinet shown in Fig. 1; and

Fig. 3 is a side elevational view of the refrigerator cabinet shown in Figs. 1 and 2, as viewed from the left hand side thereof.

The rear and other side of the refrigerator cabinet, not shown in the drawing, are substantially plain.

I claim:

The ornamental design for a refrigerator cabinet, substantially as shown and described.
